The ornamental design for a bib scarf, as shown and described.

DESCRIPTION

FIG. 1 is a top perspective view of a first embodiment of a bib scarf in an open position.

FIG. 2 is a front elevation view of the first embodiment of the bib scarf the open position.

FIG. 3 is a back elevation view of the first embodiment of the bib scarf in the open position.

FIG. 4 is a left side elevation view of the first embodiment of the bib scarf in the open position.

FIG. 5 is a right side elevation view of the first embodiment of the bib scarf in the open position.

FIG. 6 is a top plan view of the first embodiment of the bib scarf in the open position.

FIG. 7 is a bottom plan view of the first embodiment of the bib scarf in the open position.

(Continued)

FIG. 8 is a perspective view of the first embodiment of the bib scarf in a closed position. The unclaimed tag illustrated in FIG. 8 lies flat in the open position but projects away from the bib scarf in the closed position.

FIG. 9 is a front elevation view of the first embodiment of the bib scarf in the closed position.

FIG. 10 is a back elevation view of the first embodiment of the bib scarf in the closed position.

FIG. 11 is a left side elevation view of the first embodiment of the bib scarf in the closed position.

FIG. 12 is a right side elevation view of the first embodiment of the bib scarf in the closed position.

FIG. 13 is a top plan view of the first embodiment of the bib scarf in the closed position.

FIG. 14 is a bottom plan view of the first embodiment of the bib scarf in the closed position.

FIG. 15 is a top perspective view of a second embodiment of a bib scarf in an open position.

FIG. 16 is a front elevation view of the second embodiment of the bib scarf in the open position.

FIG. 17 is a back elevation view of the second embodiment of the bib scarf in the open position.

FIG. 18 is a left side elevation view of the second embodiment of the bib scarf in the open position.

FIG. 19 is a right side elevation view of the second embodiment of the bib scarf in the open position.

FIG. 20 is a top plan view of the second embodiment of the bib scarf in the open position.

FIG. 21 is a bottom plan view of the second embodiment of the bib scarf in the open position.

FIG. 22 is a perspective view of the second embodiment of the bib scarf in a closed position. The unclaimed tag illustrated in FIG. 22 lies flat in the open position but projects away from the bib scarf in the closed position.

FIG. 23 is a front elevation view of the second embodiment of the bib scarf in the closed position.

FIG. 24 is a back elevation view of the second embodiment of the bib scarf in the closed position.

FIG. 25 is a left side elevation view of the second embodiment of the bib scarf in the closed position.

FIG. 26 is a right side elevation view of the second embodiment of the bib scarf in the closed position.

FIG. 27 is a top plan view of the second embodiment of the bib scarf in the closed position.

FIG. 28 is a bottom plan view of the second embodiment of the bib scarf in the closed position; and,

FIG. 29 is a perspective view of the second embodiment of the bib scarf in the closed position, as worn by a subject. The broken lines showing the subject in FIG. 29 represent environment and form no part of the claimed design.

The broken lines shown as large dashed lines represent stitching seams of the bib scarf that form no part of the claimed design.

The broken lines shown as small dashed lines represent portions of the bib scarf that form no part of the claimed design.
